RAY H. MANSON, OF ELYRIA, OHIO, ASSIGNOR TO THE GARFORD MANUFACTURING COMPANY, OF ELYRIA, OHIO, A CORPORATION OF OHIO.

TELEPHONE.

1,178,021.

Specification of Letters Patent.

Patented Apr. 4, 1916.

Application filed October 23, 1913. Serial No. 796,752.

To all whom it may concern:

Be it known that I, RAY H. MANSON, a citizen of the United States, residing at Elyria, in the county of Lorain and State of Ohio, have invented certain new and useful Improvements in Telephones; and I do hereby declare the following to be a full, clear, and exact description of the invention, such as will enable others skilled in the art to which it appertains to make and use the same.

My invention relates to improvements in telephones, and especially to telephones adapted for field use, such as in the military service or in the linemen's service, the particular improvement being more especially directed to the switch hook mechanism.

One of the objects of my invention is to provide an arrangement whereby the switch hook lever may be protected from knocks and blows to which it is necessarily exposed in the uses to which I have referred. When the telephone is in use, it is desired to have the hook switch lever and especially the hook part projecting outside of and accessible from the outside of the casing in order that the same may be operated either by the hand or by the receiver or other telephone part placed upon the hook. When, however, the telephone set is not in use, it is desirable to have the switch hook lever retired to a protected position where it will not be exposed to the knocks and blows which the set encounters in being transported. In the field service of the army the sets are dumped into wagons or trains where they are tumbled about the same as any other equipment, coming in contact with various articles and encountering rough usage for apparatus of this type. Any exposed parts are apt to be injured. When used by linemen, the sets are likewise tumbled about, sometimes being dropped from poles or otherwise subjected to blows which injure any exposed apparatus.

In accomplishing the objects of my invention I aim to provide a hook switch lever which may be moved to normal position with the hook part projecting outside of the casing and when in such position movable to operate the switch mechanism. When in this position the hook switch lever is best maintained there by some means, such as a yielding device which permits the hook switch lever to be moved to a position

where it is protected, for example, by the casing. When in retired position I consider it best to provide means to prevent its operating the switch mechanism, since it is not desired to operate this mechanism during the transportation of the telephone set.

Other objects and aims of my invention and the invention itself will be probably better understood from a description of a particular embodiment of the invention.

Figure 1 is a plan view of an embodiment. Fig. 2 is a side elevation with the switch hook lever thrust within the casing. Fig. 3 is a side elevation showing the switch hook lever with a portion projecting beyond the casing and the same operating the switch mechanism. Fig. 4 is a detailed view with the apparatus in the same position as shown in Fig. 3 except that the switch hook lever is not operating the switch mechanism. Fig. 5 is a detailed view showing a front elevation of certain parts.

Referring now to the drawing and to the particular embodiment of my invention illustrated therein, at 6 is shown a portion of a telephone casing which is here illustrated as being made of wood, though any suitable material may be employed, such as metal. A switch mechanism is shown at 8 mounted in any suitable manner and preferably supported within the casing by a bracket 13, which may be screwed or bolted to the casing. I contemplate any suitable switch mechanism. In the form shown this consists of contact springs 9, 10 and 11 connected through insulating members 12 to the bracket 13 by suitable means, such as screws 14.

The bracket 13 is here shown as consisting of an angle plate provided with a vertical portion 15 and a top or horizontal part 16. The horizontal part is provided with a projecting lug 17 to which the switch mechanism is connected. A switch mechanism operating member consisting of a hook switch lever is shown at 20. This lever when in normal position projects through an opening 8 provided in the casing, so that the hook portion 21 is accessible from the outside of the casing, where it may be operated by the hand or other means. A portion of the talking set may be suspended from the hook 21 moving the hook to the position shown in Fig. 4 where the switch mechanism is unoperated. When this portion of the

talking set is removed from the hook 21, the hook is moved to the position shown in Fig. 3, operating the switch mechanism. This portion of the operation is well known to those skilled in the art and will not be described here in detail.

Suitable means are provided for moving the lever from the position in Fig. 4 to the position in Fig. 3, when relieved from the weight of the receiver or other portion of the talking set suspended from the hook. This is shown here as a spring 22, connected at one end to a lug 23 on the bracket 13, to which it may be attached by screws 24. The other end 25 engages the lever when in normal position, as illustrated in Figs. 3 and 4. The spring 22 is under normally downward tension, so that it tends at all times to expand, constituting means for holding the lever in the positions illustrated in Figs. 3 and 4, but yielding when the lever is thrust inwardly or to the rear, as illustrated in Fig. 2.

The lever is best pivoted, and in the form shown, a pivot is illustrated at 30 mounted on the bracket 13, the switch hook lever being rotated about the member 30 when moved from the position shown in Fig. 4 to the position shown in Fig. 3. A lug 31 is also provided upon the switch hook lever for operating the switch mechanism. The lever 20 is also provided with suitable means for engaging the pivot when in the position shown in Figs. 3 and 4. This may consist of a second hook 33 facing oppositely to the hook 21. A socket or gap 35 is provided in the hook switch lever adjacent the hook 33 into which the pivot 30 fits, when in the position shown in Figs. 3 and 4. A second gap or socket 50 is provided into which the pivot 30 fits when the lever is in the position shown in Fig. 2. An elevation or hump 34 is provided on the lever between these sockets. I may arrange the hook 33 and socket 35 as I have shown in the form illustrated so as to prevent the further withdrawal of the hook switch lever 20 from the telephone casing beyond the position shown in Fig. 3, though permitting the insertion of the hook switch lever within the casing. If it is attempted to withdraw the hook further from the casing than illustrated in Fig. 3, the hook 33 engages the pin 30 and is held, preventing a further withdrawal.

55 The hook switch lever is adapted to be moved to a position where it is protected by the casing. As here shown, it is moved within the casing, as illustrated in Fig. 2. Where a wooden casing is used as I have illustrated, it is not necessary to move the hook switch entirely beyond the inside wall of the casing, as I may simply thrust it inside the outer side of the wall, as illustrated in Fig. 2. Under these circumstances, 60 I prefer to cut away a portion of the wall

of the casing, as illustrated at 100, in order that the end of the lever may be caught between the fingers and withdrawn.

When it is desired to retire the lever, pressure is applied to the end 21 and it is shoved inwardly. The inclined edge 48 of the lug 40 on the lever engages the edge 41 of the bracket, forcing the lever downward and overcoming the pressure of the spring 22. The pivot rides over the hump 34 and into the socket 50, the top of the lug 40 engaging the top 13 of the bracket and the bottom of the socket 50 engaging the pivot 30 preventing the lever from rising, so that it will not be possible to operate the switch mechanism when the lever is in the retired position, illustrated in Fig. 2.

I have thus illustrated and described one embodiment of my invention. I do not, however, wish to be limited to this particular embodiment as I contemplate numerous and extensive departures therefrom without departing from the spirit of my invention which is described concisely in the claims.

I claim:

1. In a device of the class described, the combination of a telephone casing, switch mechanism mounted therein, a movable member controlling said switch mechanism, said member being movable to two positions, when moved to one of said positions one end of said member projecting beyond the casing and means to prevent the withdrawal of said member from said casing, said member being movable to the second of said positions where it is under the protection of the casing apparatus to positively hold said movable member in said casing and yielding means controlling the holding operation of said apparatus on said member.

2. In a device of the class described, the combination of a telephone casing, a telephone switch hook lever slidably mounted in said casing, switch mechanism controlled by said lever, said lever when in normal position projecting with the hook outside of the casing, yielding means holding said lever in normal position and means to prevent the withdrawal of the lever from the casing, said means permitting the retirement of the lever to a position under the protection of the casing.

3. In a device of the class described, the combination of a telephone casing, a switch hook lever in said casing, when in normal position having the hook projecting beyond the casing, switch mechanism controlled by said lever, and yielding means holding said lever in normal position, said means yielding when pressure is applied to the hook end of said lever to permit the retirement of said lever to a position under the protection of the casing.

4. In a device of the class described, the combination of a telephone casing, a hook

switch lever mounted in said casing, the hook on said lever extending beyond the casing when said lever is in normal position, yielding means to hold said lever in 5 normal position, said means yielding when the lever is thrust inwardly to a second position under the protection of the casing, said yielding means retaining said lever in said second position.

10 5. In a device of the class described, the combination of a telephone casing having an opening therein, a switch hook lever, switch mechanism controlled by said lever, said lever when in normal position projecting through the opening in the casing with the hook on the outside of the casing, said lever adapted to be thrust inwardly to a second position where the hook is under the protection of the casing and means for positively and securely holding said lever in said position.

15 6. In a device of the class described, the combination of a telephone casing having an opening therein, switch mechanism in the casing, a hook switch lever in the casing, when in normal position extending through the opening in the casing with the hook on the outside thereof, means to prevent the withdrawal of the hook switch lever from 20 the casing, said hook switch lever being adapted to be moved to a second position where the hook is under the protection of the casing, means for holding the hook switch lever in said position, and a spring 25 controlling the holding of said lever by said means.

20 7. In a device of the class described, the combination of a telephone casing having an opening therein, switch mechanism in the 40 said casing, a hook switch lever when in normal position projecting through the opening in the casing with the hook on the outside of the casing, said switch hook lever adapted to operate said switch mechanism 45 when in normal position, said switch hook lever being movable to a retired position under the protection of the casing and means to prevent the switch hook lever from operating switch mechanism when in the retired 50 position.

25 8. In a device of the class described, the combination of a telephone casing having an opening therein, switch mechanism in the casing, a switch hook lever pivoted in the casing, when in normal position projecting with the hook outside of the casing and adapted to operate the switch mechanism, means to prevent the withdrawal of the 30 switch hook lever from the casing, means to retire the switch hook lever to a position where it is protected by the casing and means to prevent the operation of the switch mechanism by the lever when said lever is in retired position.

35 9. In a device of the class described, the

combination of a telephone casing having an opening therein, a talking circuit, switch mechanism in said casing, a switch hook lever pivoted in said casing adapted to be moved upon the pivot to operate the switch 70 mechanism, said lever adapted to be moved to retired position and means to prevent said lever operating said switch mechanism when the lever is retired within the casing.

10 5. In a device of the class described, the combination of a telephone casing having an opening therein, switch mechanism within the casing, a switch hook lever when in normal position projecting through the opening in the casing with one end outside 80 the casing, a pivot for said lever, means to move the lever on said pivot to operate said switch mechanism when said lever is in normal position and means to withdraw the lever from switch mechanism operating position 85 when the lever is thrust within the casing.

11 6. In a device of the class described, the combination of a telephone casing having an opening therein, switch mechanism in the 90 casing, a telephone switch hook lever mounted in the casing and when in normal position projecting through the opening with the hook outside the casing, said switch hook lever being movable to switch mechanism operating position, yielding means for holding said switch hook lever in switch mechanism operating position and means for withdrawing said switch hook lever from switch mechanism operating position 95 when the lever is thrust inside the casing.

12 7. In a device of the class described, the combination of a telephone casing having an opening therein, switch mechanism in the casing, a hook switch lever when in normal 105 position projecting through said opening with the hook on the outside of the casing, when in such position the switch hook lever being movable to operate the switch mechanism, yielding means for holding such 110 switch hook lever in such position, means to prevent the withdrawal of the switch hook lever from the casing, means to withdraw said switch hook lever from switch operating position when the lever is thrust inwardly and means to prevent the switch hook lever from operating the switch mechanism when it has been withdrawn from 115 normal position.

13 8. In a device of the class described, the combination of a telephone casing, a talking circuit, switch mechanism and means to mount the same within the casing, a switch hook lever slidably mounted in said casing adapted to be slid to an outward position in 120 which the hook is outside the casing, said lever controlling said switch mechanism when in such position, apparatus to yieldingly hold said lever in such position, said hook lever slidable to a retired position in 125 130

- which the hook is within the outer wall of the casing, means to remove said switching mechanism from the control of the hook lever when said hook lever is removed to a retired position, said apparatus yieldingly holding said lever in retired position.
14. In a device of the class described, the combination of a telephone casing, a telephone switch-lever having a hook on its outward end for a receiver or similar instrument, said lever being movably mounted in said casing, switch mechanism controlled by said lever, said lever when in normal position projecting with the hook end
- (10)

outside of said casing, yielding means controlled by said lever holding said lever in normal position and means to prevent the withdrawal of the lever from the casing, said means permitting the retirement of the lever to a position under the protection of the casing.

In witness whereof, I have affixed my signature in the presence of two witnesses this 18th day of October, 1913.

RAY H. MANSON.
